UNITED STATES PATENT OFFICE.

CHARLES R. HARRIS, OF WILLIAMSPORT, PENNSYLVANIA.

DESIGN FOR A BUCKLE.

SPECIFICATION forming part of Design No. 24,574, dated August 20, 1895.

Application filed July 6, 1895. Serial No. 565,165. Term of patent 7 years.

To all whom it may concern:

Be it known that I, CHARLES R. HARRIS, a citizen of the United States, residing at Williamsport, in the county of Lycoming and State of Pennsylvania, have invented and produced a new and original Design for Suspender Clasps or Buckles, of which the following is a specification, reference being had to the accompanying drawings, showing a part thereof.

Figure 1 is a view in front elevation showing my clasp or buckle applied to a suspender-web, and Fig. 2 is a vertical section.

The leading feature of my design consists in the representation of a scallop of fringe.

A is the back-plate of a clasp or buckle, and B the lever hinged thereto. This lever is for the most part made to represent a scallop of fringe, the fringe depending from the clamping-bar C at the upper end of the lever. 20

What I claim is—

The design for clasps or buckles herein shown and described.

CHARLES R. HARRIS.
